UNITED STATES PATENT OFFICE.

CLYDE C. FARMER, OF PITTSBURGH, PENNSYLVANIA, ASSIGNOR TO THE WESTINGHOUSE AIR BRAKE COMPANY, OF WILMERDING, PENNSYLVANIA, A CORPORATION OF PENNSYLVANIA.

RETARDED RELEASE-VALVE DEVICE.

Application filed September 8, 1925. Serial No. 54,887.

This invention relates to fluid pressure brakes and more particularly to a triple valve device.

When triple valve devices are being operated in service, it occasionally happens that the triple valve piston becomes cocked in the piston cylinder, thereby causing faulty operation of the triple valve device.

One object of my invention is to obviate the above difficulty by providing an improved guiding means for the piston.

Where my improved piston guide is employed in connection with a triple valve device of the retarded release type, the usual retarded release stop would interfere with the installation of the guide and therefore a further object of my invention is to provide a retarded release stop adapted to be employed with the improved piston guide.

In the accompanying drawing; Fig. 1 is a vertical section of a triple valve device embodying my invention; Fig. 2 a partial transverse section of the triple valve device showing the improved retarded release stop device; and Fig. 3 a side elevation of the retarded release stop device.

As shown in the drawing, the triple valve device may comprise a casing 1 having a piston chamber 2 containing a piston 3, which is adapted to operate main slide valve 5 and graduating slide valve 6 through stem 4, said valves being disposed in slide valve bushing 7, which is fitted in casing 1.

According to my invention, the casing 1 is provided with an opening at one end adapted to be closed by a plug 8 having screw-threaded engagement with the casing 1. The plug 8 is provided with an inwardly extending portion 9 having a central bore 10 in accurate alignment with the piston cylinder 2. The piston stem 4 is provided with a rearwardly extending cylindrical guide portion 22, which is adapted to engage and have a neat sliding fit in the bore 10.

In order to provide for retarded release, a retarded release stop is employed, comprising a tubular member 11 adapted to be applied over the guide portion 22 and having an outwardly flaring flange 12 at one end adapted to engage the end of the slide valve bushing 7, and an inwardly extending flange 13 spaced from the other end and adapted to engage a collar 14 on piston stem 4.

Slots 15 and 16 are provided in member 11, so as to receive corresponding downwardly extending feet of collar portion 14 of the piston stem, thus enabling the member 11 to extend past said collar portion and engage the end of slide valve 5. At the inner ends of the slots 15 and 16 the member 11 is provided with downwardly extending feet 17 and 18 adapted to engage in a rectangular recess 19 in slide valve bushing 7 so as to prevent rotation of the member 11.

In order to yieldingly maintain the member 11 in its normal full release position, a coil spring 20 is interposed between the flange 13 and the plug 8.

When fluid under pressure on opposite sides of piston 3 is equalized, said piston and consequently slide valves 5 and 6 are maintained in the normal full release position, as shown in Fig. 1 of the drawing.

After the brakes have been applied in the usual manner, if it is desired to release the brakes, the brake pipe pressure is increased. At the head end of the train where the increase in brake pipe pressure is at a rapid rate, the triple valve piston 3 is shifted to its innermost or retarded release position, moving the release stop member rearwardly against the resistance of spring 20. At the rear of the train, where the rate of increase in brake pipe pressure is less than at the head end, the triple valve piston will only move to full release position, in which the slide valve 5 engages the retarded release stop 11.

The provision of the extended guide member 22 in connection with the triple valve piston stem 4, serves to prevent cocking of the triple valve piston, and where employed with a retarded release triple valve device, I have provided a release stop adapted to be applied in connection with the guide member.

Having now described my invention, what I claim as new and desire to secure by Letters Patent, is:—

1. A triple valve device comprising a casing having a piston chamber and a valve chamber, a piston in said piston chamber, a slide valve mounted in said valve chamber, a piston stem carried by said piston for operating said valve, a guide member extending rearwardly of said stem, a collar

disposed between said stem and said extension, and a tubular stop member engaging said valve and having a flange engaging said collar.

5 2. The combination with a triple valve device having a piston and a slide valve operable by said piston, of a retarded re-

lease stop device comprising a movable tubular member engaging said valve, and a spring for opposing movement of said member. 10

In testimony whereof I have hereunto set my hand.

CLYDE C. FARMER.
